ELECTRIC CONTROL DEVICE

Lawrence J. Dahline and William J. Field, Minneapolis, Minn., assignors to Minneapolis-Honeywell Regulator Company, Minneapolis, Minn., a corporation of Delaware

Application March 13, 1944, Serial No. 526,288

15 Claims. (Cl. 171--242)

1

Our invention relates to electric control devices and has for an object to produce a control device responsive to a feeble variable actuating force and operating to produce an appreciable corresponding controlling force.

Another object of the invention resides in providing a control device which requires an exceedingly small amount of energy to operate.

A feature of the invention resides in providing a control device which will produce force or movement of the controlled member substantially proportional to the torque or movement of the actuating member.

A feature of the invention resides in providing an electric control device which will be unaffected by the operation of another control device or other electric apparatus positioned in the vicinity thereof.

A still further object of the invention resides in providing an electric control device in which flexible leads, slip rings or other sliding contacts are eliminated.

Another object of the invention resides in providing a control device which will be simple in construction and positive and effective in operation.

Other objects of the invention reside in the novel combination and arrangement of parts and in the details of construction hereinafter illustrated and/or described.

In the drawings:

Fig. 1 is a plan view of an electric control device illustrating an embodiment of our invention.

Fig. 2 is an elevational view, parts being sectioned along the line 2—2 of Fig. 1.

Fig. 3 is an elevational view, parts being sectioned along the line 3—3 of Fig. 1.

Fig. 4 is a plan view, parts being sectioned along the line 4—4 of Fig. 2.

Fig. 5 is a perspective view of the rotor used with the device illustrated in Figs. 1 and 4.

Figs. 6, 7, 8 and 9 are perspective views of different forms of rotors capable of use with our invention.

Fig. 10 is a wiring diagram of a circuit in which our invention may be used.

In control devices of the prior art, considerable force or torque is required to move the operating member of the device. The present invention overcomes this objection by providing a construction utilizing the principle of eddy currents and in which an extremely small resistance to the movement of the operating member of the device

2

results so that the device is responsive to relatively weak actuating forces.

Our invention comprises a magnetic core structure 21, operating in conjunction with which is a rotor 22 functioning as a short-circuited conductor indicated in its entirety by the reference numeral 23, and comprising a member having the shape of a deformed or incomplete cylinder. The core structure 21 is supported on a base 24, while the rotor 22 is supported for rotation by means of a frame 25 also carried by said base. These parts will now be described in detail.

The core structure 21 is constructed from a number of laminations 26 which are E-shaped in form and which, when assembled, form the core structure 21 also E-shaped in form, which has a center leg 27 and two outer legs 28 and 29 connected together by means of a yoke or connecting portion 31. The upper end of the leg 27 has attached to it a transverse core member 32 which is held in place between the outermost laminations 26a of the core structure 21 by means of rivets 33 which extend jointly through said laminations and transverse core member. The core member 32 has opposing ends 34 and 35 which lie in proximity to the facing surfaces 36 and 37 of the legs 28 and 29, and form air gaps 38 and 39 therebetween. The core structure 21 is attached to the base 24 which is preferably formed of insulating material by means of two clip angles 41 which are secured to the connecting portion 31 of the core structure by means of a rivet 42. Screws 43 pass through these clip angles and are threaded into the base 24.

35 Mounted on the center leg 27 of the core structure 21 is an exciting winding 44 which is energized by a suitable pulsating current such as an alternating current or the like and which causes flux to pass through two parallel magnetic circuits indicated diagrammatically at 47 and 48, the circuit 47 including the air gap 38 and the leg 28 of the core structure and the circuit 48 including the air gap 39 and the leg 29 of the core structure. The core structure 21 is so constructed that the fluxes set up in these two circuits by the winding 44 are balanced. On the legs 28 and 29 are mounted control windings 45 and 46 which are responsive to the fluxes passing in the two magnetic circuits 47 and 48.

50 The rotor 22 is best shown in Fig. 5 and consists of a shaft 51 which has attached to it a head 52. Extending downwardly from the head 52 is an annular part 53 which constitutes a conductor indicated in its entirety by the reference numeral 23. In the forms of the invention disclosed,

the conductor 23, the head 52 and the shaft 51 are all constructed integral, though it can be readily comprehended that these parts may be separately formed and also that the head 52 may, if desired, be constructed of insulating material. Where, however, the head 52 is constructed of conducting material, the same as the annular part 53, the said head forms part of the conductor and operates in conjunction therewith, as will be subsequently more fully described.

The frame 25 includes a cross bar 55 which is formed with a bearing 54 in which the shaft 51 of rotor 22 is journaled. The frame 25 further includes two posts 56 and 57 which are secured to the base 24 by means of screws 58. Other screws 59 extend through the cross-bar 55 and are threaded into the posts 56 and 57 and secure said cross-bar in position to support the rotor 22 for rotation. A washer 60 disposed between the cross-bar 55 and the head 52 of the rotor, holds the said head in spaced relation relative to said cross-bar. A collar 61, secured to the outermost end of the shaft 51 by means of a set screw 62, serves to prevent the shaft 51 from moving downwardly along the bearing 54. The protruding end 63 of shaft 51 is connected to the movable element of the actuating device which provides the actuating force or torque and serves to operate the control device. This may be accomplished in any suitable manner by means of gearing, mechanical transmission or by directly attaching the rotor 52 to a movable member movable with the movable element of the actuating device. Where the rotor 22 is directly connected, the shaft 51 and the bearing 54 may be dispensed with and the device will operate with less resistance.

The conductor 23 has a slit 64 formed therein which extends transversely of the circumferential extent of the said conductor. This slit has a part 65 which extends through the annular part 53 of the conductor, Fig. 3, and also a part 66 which extends into the head 52. By means of this slit, the conductor 23 is divided into two portions 67 and 68 which extend up to said slit and which are integral rearwardly of the slit.

Rotor 22 is normally symmetrically arranged with respect to core structure 21, so that a radial line passing through the center of the slot is perpendicular to the line joining the centers of the poles of the core structure. Portions 67 and 68 of the rotor then offer equal impedance to the flow of eddy currents in response to the equal magnetic fluxes in magnetic circuits 41 and 48: the eddy currents are equal and these currents in turn produce equal counter fluxes. The counter fluxes are in directions to oppose the original fluxes, and accordingly the resultant fluxes are equal; they traverse the windings 45 and 46, and if the windings are identical equal voltages are introduced therein.

If rotor 22 is not in its normal position, the impedances of portions 67 and 68 thereof to eddy currents are no longer equal, and the eddy currents caused by the equal magnetic flux are also no longer equal. The counter fluxes are also unequal in the same sense, and these counter fluxes oppose the normally equal fluxes to give unequal resultant fluxes in the windings 45 and 46, thus changing the relation between the voltages introduced in the windings.

It is difficult to construct cores and wind coils so that they are completely identical electrically and mechanically, as the foregoing discussion

assumes. In order to facilitate adjusting the fluxes in magnetic circuits 41 and 48 so as to give equal potentials across the coils 45 and 46 when the device is in normal position, a short circuited conductor 191 is employed which is constructed from sheet metal, preferably copper, and which has a circular hole 192 in the center of the same adapted to receive the leg 27 of the core structure 21. This conductor has a slit 193 at the forward portion of the same which can be adjusted angularly about the center of the leg 27 by rotating said conductor about the center of the leg 27 as an axis. The conductor 191 overlies a disk 194 of insulating material which has a rectangular hole 195 in the same which snugly fits the leg 27 of core structure 21 and prevents rotation of said disk. The disk 194 is provided with an ear 196 projecting rearwardly therefrom. A bolt 197 extends jointly through said ear and through a slot 198 formed in a rearwardly projecting portion 199 of the conductor 191. By means of this construction, the conductor 191 may be held in adjusted position. The conductor 191 operates similarly to the conductor 23 and the eddy currents generated therein produces counterfluxes which unequally opposes the fluxes passing through the circuits 41 and 48, depending upon the direction of the slot 193 with reference to the plane of the magnetic circuits 41 and 48. By properly adjusting the conductor 191, these counter fluxes can be made to cause the potential across the coils 45 and 46 to become exactly equal, when the rotor is in normal position.

In Fig. 10, we have shown a wiring diagram of an electric circuit utilizing our invention. In this circuit, two electron discharge tubes 111 and 112 are employed, each having the usual plate or anode 113, grid 114 and cathode 115. In addition, a heater 116 is employed for each cathode which causes operation of the tube in the usual manner. Inasmuch as the circuit for energizing the heaters 116 is well known in the art and forms no particular feature of the invention, the same has not been shown in the drawings.

For energizing the tubes 111 and 112, a transformer 117 is employed having a secondary 118 provided with a center tap 119 and a primary 121 connected to a line 122—123 energized from any suitable source of alternating current. In the drawings, one side 123 of the line has been shown as grounded and corresponding parts of the circuit have been shown as grounded as will be presently brought out. One end of the secondary 118 of transformer 117 is connected by means of a conductor 124 with the plate 113 of tube 112 while the other end of said secondary is connected by means of a conductor 125 with the plate 113 of tube 111. The center tap 119 of the secondary 118 is connected by means of a conductor 126 with a condenser 127 which, in turn, is connected by means of conductors 128 and 129 with both of the two cathodes 115 of the tubes 111 and 112. At the same time, the conductor 128 is grounded.

The two grids 114 of tubes 111 and 112 are connected in parallel by means of conductors 131 and 132 to an amplifier 133. The amplifier 133 may be an ordinary single or multiple stage amplifier using suitable electron discharge tubes and the usual accompanying parts connected up and energized as is well known in the art. Since the amplifier forms no particular feature of the invention, the same has not been illustrated in

detail, though it can readily be comprehended that any of the well known types of amplifiers may be used.

To procure grid bias for the two grids 114, a battery 151 is employed which is connected by means of a conductor 152 to a resistance 153. The said resistance is in turn connected by means of a conductor 154 to the conductor 131.

A condenser 155 is grounded through a conductor 156 and is further connected by means of a conductor 157 to the conductor 131.

In the embodiment of the invention disclosed in Fig. 10 of the drawings, three control devices 140a, 140b and 140c have been illustrated which are connected in series in a circuit which we have termed a control circuit and which is designated by the reference numeral 159. For the sake of simplicity, the same reference numerals as previously employed, modified by a differentiating sub-character, will be used to refer to the various similar parts of said control devices. The windings 45a and 46a are connected together by means of a conductor 141a and in such a manner that the potentials set up in these windings tend to oppose each other and in the normal position of the rotor 22a just neutralize each other and produce no flow of current. The windings 45b and 46b and the windings 45c and 46c are similarly connected by means of conductors 141b and 141c. All of these windings are connected in series through conductors 142, 143, 144 and 145, the conductor 145 being grounded. Conductor 142 is connected to a blocking condenser 146 which, in turn, is connected by means of a conductor 147 to the amplifier 133.

The windings 44a, 44b and 44c are all connected in parallel through conductors 153, 159 and 161. These conductors, in turn, are connected to a conductor 162 which is connected to the side 122 of the line. The said windings 44a, 44b and 44c are further connected by means of conductors 163, 164 and 155 to ground. It will thus be readily comprehended that the windings 44a, 44b and 44c are throughout the operation of the device constantly energized by the line voltage.

The controlling element of our improved control device comprises a two-phase electric motor diagrammatically indicated at 160. This motor consists of a rotor 166 having short-circuited windings; as for example, a squirrel cage, and two stationary windings 167, 168, disposed 90 electrical degrees apart. The rotor 166 is reversible and the direction of rotation is dependent upon the phase relationship of the voltage of the said windings. Both of the windings 167 and 168 are connected to a common conductor 169 which is grounded. The winding 167 is further connected by means of a conductor 171 to the conductor 126 at a locality between the condenser 127 and the tap 119. The winding 168 is connected by means of a conductor 172 with a condenser 173, which, in turn, is connected by means of a conductor 174 with the side 122 of the line. It will thus be seen that the winding 168 is directly energized from the line, while the winding 167 is energized from the voltage across the plate circuits of the two tubes 111 and 112.

In Fig. 10, we have shown as previously stated, three control devices connected in the circuit. Such an installation is particularly useful where three variable actuating devices all function to modify the performance of a single device.

The operation of the invention is as follows: With the actuating devices exerting no torque on

the rotors 22a, 22b and 22c, said rotors would all be in normal position, and no current would flow through any of the windings 45a, 46a, 45b, 46b, 45c and 46c. Therefore, no voltage would be impressed upon the amplifier 133 and likewise, no signal voltage would be impressed upon the grids 114 of the two tubes 111 and 112. The winding 167 of motor 160 would thus be deenergized and the motor 160 would remain stationary. If, however, one of the rotors 22a, 22b or 22c were shifted out of normal position, a current would be caused to flow through the amplifier 133 and the phase of the current would depend upon the direction of shift of the said rotor. Movement of the said rotor from one side of the normal position to the other would procure reversal in phase and the degree of shift would determine the voltage impressed upon the amplifier 133. Since the tubes 111 and 112 only transmit current in one direction, one of the said tubes would serve to furnish a unidirectional pulsating current through the plate circuit of the tubes. The condenser 127 serves to convert this current into an alternating current which is impressed upon the winding 167. The value of the condenser 127 can be made such that the voltage impressed upon the winding 160 is either 90° or 270° out of phase with the voltage across the winding 168, depending upon which of the tubes 111 or 112 is passing current. Thus, the motor 160 will be energized as a two-phase motor and the direction of rotation of the same will depend upon the direction of shift of any of the rotors 22a, 22b or 22c. The motor 160 being connected to the device to be controlled, corrects the position of the device until the particular rotor 22a, 22b or 22c which actuated the control device returns to normal position.

In Figs. 6, 7, 8 and 9, we have shown various modifications of the rotor 22 shown in Fig. 5 which modifications produce variations in performance of the control device. These various rotors are similar in construction and for the sake of simplicity, the description of each device will not be repeated and similar reference characters, to which have been added different sub-characters, will be used to designate corresponding parts.

The rotor 22 may, if desired, be constructed as shown in Fig. 6, with the slot 64 substantially closed, as indicated at 181. With the rotor so constructed, maximum shielding is procured, so that the device is less affected by stray magnetic fields. With this form of the invention, however, the sensitivity at normal position is not as great as with that shown in Fig. 5.

In Fig. 7, the slot has been expanded until the shape of the rotor is hemicylindrical. With this form of the invention, the voltage at normal position never quite reaches zero, so that an initial voltage tending to operate the device is always present, which makes the device more sensitive at such position. However, in this case, the shielding effect is considerably less pronounced.

Where it becomes desirable to produce a device in which the voltage impressed on the amplifier varies proportionately with the angle of displacement of the rotor, a rotor shaped as indicated at Fig. 8 can be employed. It will here be noted that the lower edge 182 of the rotor is in the form of a helix, so that the length of the annular part 53y of the said rotor progressively increases in a direction away from the slot 54y. It has been found that a device so constructed produces the

desired results almost up to the point where the slot reaches the air gaps 38 and 39.

Where it becomes desirable to have the device operate at two angular positions intermediate the extreme positions of the rotor, the rotor can be constructed as shown in Fig. 9. In this form of the invention, the lower edge 183 is constructed similar to the edge 182 of the rotor shown in Fig. 8, the difference in this construction being that the slot 642 is disposed at the longest part of the annular portion 532.

The advantages of our invention are manifest. The device can be constructed so as to produce different types of performance in accordance with the requirements. If desired, different degrees of shielding can be procured so as to prevent interference from other control devices or other electrical apparatus. The device is simple in construction and positive in action. With our invention, there are no flexible leads, slip rings, brushes or other movable contacts associated with the rotor of the invention. The moving part of our invention requires a minimum amount of energy to operate and, in certain applications, may be directly connected to the actuating member, whereby bearing friction of the control device is entirely eliminated.

Changes in the specific form of our invention, as herein described, may be made within the scope of what is claimed without departing from the spirit of our invention.

Having described our invention, what we claim as new and desire to protect by Letters Patent is:

1. An electric control device comprising a magnetic core structure providing two magnetic circuits each including a single air gap, means which upon energization is adapted to produce opposed pulsating magnetic fluxes in said circuits normally balancing one another, a short circuited conductor having portions adapted to extend into said air gaps, said conductor being formed with a single slit therein disposed exteriorly of the air gaps and between said portions, means for supporting said conductor for movement to cause said slit to approach one air gap and to recede from the other air gap to unbalance the fluxes in said circuits and flux responsive means actuated through unbalance of the fluxes in said magnetic circuits.

2. An electric control device comprising a magnetic core structure providing two magnetic circuits each including a single air gap, means which upon energization is adapted to produce opposed pulsating magnetic fluxes in said circuits, normally balancing one another, a single annular short circuited nonmagnetic conductor having portions adapted to extend into said air gaps, said conductor being formed with a transverse slit extending in the direction of the axis thereof and separating said portions, means for supporting said conductor for rotation about its axis to cause said slit to approach one air gap and recede from the other air gap upon rotation of said conductor in one direction to unbalance the fluxes in said circuits and flux responsive means actuated through unbalance of the fluxes in said circuits.

3. An electric control device comprising a magnetic core structure providing two magnetic circuits each including an air gap, means which upon energization is adapted to produce opposed pulsating magnetic fluxes in said circuits, normally balancing one another, an annular short circuited conductor having portions adapted to extend into said air gaps, said conductor being formed with a transverse slit separating said

portions, said conductor being constructed so that the cross-sectional area thereof increases progressively to each side of the slit, means for supporting said conductor for rotation about its axis to cause said slit to approach one air gap and recede from the other air gap upon rotation of said conductor in one direction to unbalance the fluxes in said circuits, and flux responsive means actuated through unbalance of the fluxes in said air gaps.

4. An electric control device comprising a magnetic core structure providing two magnetic circuits each including an air gap, means which upon energization is adapted to produce opposed pulsating magnetic fluxes in said circuits, normally balancing one another, an annular short circuited conductor having portions adapted to extend into said air gaps, said conductor being formed with a transverse slit separating said portions, said conductor being constructed so that the cross-sectional area thereof varies progressively to each side of the slit, means for supporting said conductor for rotation about its axis to cause said slit to approach one air gap and recede from the other air gap upon rotation of said conductor in one direction to unbalance the fluxes in said circuits, and flux responsive means actuated through unbalance of the fluxes in said air gaps.

5. An electric control device comprising a magnetic core structure providing two magnetic circuits each including an air gap, means which upon energization is adapted to produce opposed pulsating magnetic fluxes in said circuits, normally balancing one another, a single tubular short circuited conductor having portions adapted to extend into said air gaps, said conductor being formed with a single transverse slit separating said portions, the axial extent of said tubular conductor varying progressively to each side of the slit, means for supporting said conductor for rotation about its axis to cause said slit to approach one air gap and recede from the other air gap upon rotation of said conductor in one direction to unbalance the fluxes in said circuits, and flux responsive means actuated through unbalance of the fluxes in said circuits.

6. An electric control device comprising a magnetic core structure E-shaped in form and having a center leg and outer legs forming two spaced air gaps therebetween, said legs providing two magnetic circuits each including one of said air gaps, means which upon energization is adapted to produce opposed pulsating magnetic fluxes in said circuits normally balancing one another, an annular short circuited conductor encircling said center leg and having portions adapted to extend into said air gaps, said conductor being formed with a single transverse slit parallel with the axis thereof and separating said portions, means for supporting said conductor for rotation about its axis, said axis extending longitudinally of the center leg to cause said slit to approach one air gap and recede from the other air gap upon rotation of said conductor in one direction to unbalance the fluxes in said circuits, and flux responsive means actuated through unbalance of the fluxes in said circuits.

7. An electric control device comprising a magnetic core structure E-shaped in form and having a center leg and outer legs forming two spaced air gaps therebetween, said legs providing two magnetic circuits each including one of said air gaps, a winding on said center leg adapted upon energization to produce opposed pulsating mag-

netic fluxes in said circuits, normally balancing one another, an annular short circuited conductor encircling said center leg and enveloping and shielding said winding, said conductor having portions adapted to extend into said air gaps, and being formed with a single transverse slit parallel with the axis thereof and separating said portions, means for supporting said conductor for rotation about an axis extending longitudinally of the center leg to cause said slit to approach one air gap and recede from the other air gap upon rotation of said conductor in one direction to unbalance the fluxes in said circuits and flux responsive means actuated through unbalance of the fluxes in said circuits including windings on said outer legs.

8. An electric control device comprising a magnetic core structure E-shaped in form and having a center leg and outer legs forming two spaced air gaps therebetween, said legs providing two magnetic circuits each including one of said air gaps, a winding on said center leg adapted upon energization to produce opposed pulsating magnetic fluxes in said circuits normally balancing one another, a cup shaped short circuited conductor having a head and an annular part encircling said center leg and said winding with its axis extending in the direction of extent of said center leg and with portions extending into said air gaps, said conductor being formed with a slit extending transversely of the circumferential extent thereof and separating said portions, means for supporting said conductor for rotation about its axis, to cause said slit to approach one air gap and recede from the other air gap upon rotation of said conductor in one direction to unbalance the fluxes in said circuits, and flux responsive means actuated through unbalance of the fluxes in said circuits.

9. An electric control device comprising a magnetic core structure E-shaped in form and having a center leg and outer legs forming two spaced air gaps therebetween, said legs providing two magnetic circuits each including one of said air gaps, a winding on said center leg adapted upon energization to produce opposed pulsating magnetic fluxes in said circuits normally balancing one another, a cup shaped short circuited conductor having a head and an annular part encircling said center leg and said winding and having portions adapted to extend into said air gaps, said conductor being formed with a slit extending transversely of the circumferential extent thereof and separating said portions, means for supporting said conductor for rotation about an axis extending longitudinally of the center leg, to cause said slit to approach one air gap and recede from the other air gap upon rotation of said conductor in one direction to unbalance the fluxes in said air gaps and a second short circuited conductor encircling said center leg and cooperating with said first named conductor to shield said winding.

10. In combination, a control circuit, a control device comprising a magnetic core structure providing two magnetic circuits each including an air gap, exciting means for producing in said air gaps opposed pulsating magnetic fluxes normally balancing one another, a short circuited conductor having portions adapted to extend into said air gaps, means for supporting said conductor for movement to cause said portions to move transversely of the direction of extent of the air gaps, to unbalance the fluxes in said air gaps, current conducting means responsive to un-

balance of the fluxes in said air gaps, said current conducting means being connected in said control circuit and a second control device similar to said first named control device and excited by the same exciting means, the current conducting means of said second control device being connected in said control circuit and in series with the current conducting means of said first named control device and a second short circuited conductor associated with the short circuited conductor of said first named control device and adjustable relative thereto to vary the phase relation between said first named device and said second named device.

11. In combination, a control circuit, a magnetic core structure providing two magnetic circuits, exciting means for producing opposed pulsating magnetic fluxes in said circuits normally balancing one another, a short circuited conductor having portions adapted to intercept the fluxes passing through said circuits, means for supporting said conductor for movement to cause said portions to move transversely of the direction of extent of the fluxes in said circuits to unbalance the fluxes in said circuits, current conducting means responsive to unbalance of the fluxes in said magnetic circuits, said current conducting means being connected in said control circuit and a second control device similar to said first named control device, the current conducting means of said second control device being connected in said control circuit and in series with the current conducting means of said first named control device and a second short circuited conductor associated with the short circuited conductor of said first named control device and adjustable relative thereto to vary the phase relation between said first named device and said second named device.

12. An electric control device comprising magnetic core means providing a plurality of pairs of magnetic circuits, means which upon energization is adapted to produce pulsating magnetic fluxes in all of said magnetic circuits with the fluxes in each pair of magnetic circuits balancing one another, a plurality of short circuited conductors, one for each pair of magnetic circuits, each of said conductors having a portion adapted to intercept the fluxes passing through each of the magnetic circuits of the pair, means for supporting each of said conductors for independent movement to cause the denoted portions of said conductors to move transversely of the direction of extent of the fluxes intercepted by them to unbalance said fluxes some of said magnetic circuits having a second short circuited conductor associated with the first named short circuited conductor thereof, said second short circuited conductors being adjustable to vary the phase relation between the pairs of magnetic circuits, flux responsive means energized in accordance with the unbalance of the fluxes in each of said pairs of magnetic circuits, a controlled device, and means connecting said controlled device with said flux responsive means for joint control thereby.

13. An electric control device comprising a magnetic core structure providing two magnetic circuits, a single air gap in each of said circuits, said magnetic circuits having a common leg provided with two poles and with other legs having complementary poles spaced from said first named poles and forming said air gaps, means which on energization is adapted to produce in said magnetic circuits balanced pulsating fluxes, both of

which at certain instants flow in the same direction from the poles of said common leg through said air gaps and to the complementary poles of the other legs, a short circuited conductor having circuitous extent with portions extending into said air gaps, said conductor being formed with a single slit therein extending transversely of the direction of extent thereof and separating said portions, said slit being disposed exteriorly of and intermediate said air gaps, means for supporting said conductor for movement in the direction of extent thereof to cause said slit to approach one air gap and to recede from the other air gap to unbalance the fluxes in said circuits and flux responsive means actuated through unbalance of the fluxes in said magnetic circuits.

14. An electric control device comprising a magnetic core structure providing two magnetic circuits, a single air gap in each of said circuits, said magnetic circuits having a common leg provided with two poles and with other legs having complementary poles spaced from said first named poles and forming said air gaps, a winding on said common leg which on energization is adapted to produce in said circuits balanced pulsating fluxes, both of which at certain instants flow in the same direction from the poles of said common leg, through said air gaps to the complementary poles of the other legs, a cup-shaped short circuited conductor encircling the poles of said common leg and having portions extending into said air gaps, said conductor being formed with a single slit therein extending along an element of said conductor and separating said portions, said slit being disposed exteriorly of and intermediate said air gaps, means for supporting said conductor for movement about the axis of said conductor, said axis being located at the axis of said common leg, said conductor enveloping said winding about the sides and one end thereof, a

disk-like short-circuited conductor disposed at the open end of said cup-shaped conductor and further enveloping said winding, said second conductor having a slit therein disposed exteriorly of and intermediate said air gaps, means for adjustably supporting said second conductor and flux responsive means actuated through unbalance of the fluxes in said magnetic circuits.

15. An electric control device comprising a magnetic core structure providing two magnetic circuits, a single air gap in each of said circuits, said magnetic circuits having a common leg provided with two poles and with other legs having complementary poles spaced from said first named poles and forming said air gaps, means which on energization is adapted to produce in said magnetic circuits balanced pulsating fluxes, both of which at certain instants flow in the same direction from the poles of said common leg through said air gaps and to the complementary poles of the other legs, a C-shaped short circuited conductor encircling said common leg and having portions extending into said air gaps, means for supporting said conductor for movement in the direction of extent thereof to unbalance the fluxes in said magnetic circuits and flux responsive means actuated through unbalance of the fluxes in said magnetic circuits.
